GEORGE M. HAMILTON, OF OAKMONT, PENNSYLVANIA; MARGARET T. HAMILTON
ADMINISTRATRIX OF SAID GEORGE M. HAMILTON, DECEASED.

FUEL-CONTROL MECHANISM FOR INTERNAL-COMBUSTION ENGINES.

Application filed December 31, 1920. Serial No. 434,311.

To all whom it may concern:

Be it known that I, GEORGE M. HAMILTON, a citizen of the United States, residing at Oakmont, in the county of Allegheny and 5 State of Pennsylvania, have invented certain new and useful Improvements in Fuel- Control Mechanism for Internal-Combustion Engines, of which the following is a specification.

10 My invention is an improvement in internal combustion engines, and particularly in the motors of this type as used on automobiles or similar self-propelled vehicles.

It has in view to provide means for cutting off the fuel supply to the explosion chamber or chambers of the engine at times when the car is running upon its own momentum, as in coasting, and for simultaneously reducing the vacuum of the cylinders, and increasing the compression and resulting resistance.

Primarily, it has in view to effect a corresponding economy in the use of the explosive fuel at such times as the engine is operating 25 by motion transmitted to it from the traction wheels and connected gearing.

Ordinarily, in such cases, the conduit between the fuel supply, as a carburetor, and the explosion chamber or chambers of the 30 cylinder or cylinders is normally more or less open, so that when the engine is itself being operated by the turning over of the crank shaft and corresponding actuation of the plungers, there is an undesired suction 35 of the fuel and a wasting thereof through the ordinary exhaust passages.

My invention has in view not only to provide means for cutting off the communication 40 between the fuel supply and the explosive chamber or chambers at such times as propelling power is not needed and at the same time opening communication from the cylinder or cylinders to the atmosphere so as to ensure an ample supply of air with 45 resulting higher compression and a lower vacuum in the cylinders, but to effect such operation automatically through mechanism controlled by the conditions of the engine itself and its manifold.

50 Also, to provide means which are sufficiently sensitive to the varying conditions of suction (i. e., vacuum) as exerted through the manifold and which will actuate operating mechanism adapted to promptly and 55 positively respond to varying conditions to

open and close the fuel supply and with a controlled accompanying air supply to the manifold.

The invention not only contemplates the simultaneous closing of the fuel supply and 60 opening of the circulation to the atmosphere, and vice versa, and regulating valve mechanism, but also the operation and control of the valve mechanism through means directly affected by the vacuum conditions in 65 the manifold, utilizing a vacuum actuated member and connected spring controlled lever mechanism for opening and closing connection between the manifold or atmosphere respectively, for operation of the fuel 70 and air regulating valve.

The invention utilizes a rotatable cock or valve and actuating mechanism therefor controlled by a separate valve which itself is subject to means directly communicating 75 with the manifold or other conduit leading to the explosive chamber or chambers and subject to the conditions therein at all times.

The invention also provides for positive 80 independent manual operation of the said lever mechanism for utilizing the manifold conditions, and various other features of construction and advantage as shall be more fully hereinafter set forth. 85

The invention is somewhat similar in purpose and operation to that disclosed in my prior application filed July 13, 1920, Serial No. 396,028.

In the drawings, which illustrate one preferred embodiment of the invention,

Fig. 1 is a vertical sectional view through a valve mechanism interposed between the fuel supply and the manifold leading to the engine, partly broken away, showing the fuel 95 supply open and the air supply closed;

Fig. 2 is a sectional detail view of a controlling check valve as interposed between the manifold and the lever-actuating suction-controlled mechanism;

Fig. 3 is a view similar to Fig. 1, but showing the fuel supply closed and the air supply open; and,

Fig. 4 is a detail plan view of the spring controlled lever mechanism for the circulation controlling valve between the manifold and the suction-actuated fuel valve controlling mechanism.

In the drawings, C represents the upper portion of a carburetor or other fuel supply 110

device of any well known construction. The manifold M, also of any ordinary type, leads to the explosion chamber or chambers of one or more cylinders communicating therewith by the usual lateral ports.

Between the carburetor and the manifold is inserted my improved regulating device which consists of a suitable casing 2 having direct communication with the carburetor 10 C by a conduit 3 opening into a middle cylindrical valve seated chamber 4 of casing 2. Beyond the valve chamber 4 is a conduit 5 leading by a communicating conduit 6 to the engine manifold M. Casing 2 is also provided with an air inlet valve V opening to the atmosphere by ports 7 and communicating directly with chamber 4 of casing 2 by a valve controlled port 8 between conduits 3 and 5.

20 Within chamber 4 of casing 2 is a rotatable valve 9 having a ported opening whereby to put the fuel supply in communication with the manifold, as in Fig. 1, with air supply closed, or to close the fuel supply and furnish air to the manifold, as in Fig. 3, dependent on the position of the valve. Valve 9 is provided with a lever 10 connected by stem 11 with the diaphragm 12 of a vacuum chamber 13 enclosed within 25 a suitable casing 14—15 and mounted on a supporting bracket 16 of any suitable kind. Valve 9 is normally held closed by tension spring 17 of lever 10 for fuel circulation, and is reversed by manifold suction on diaphragm 12, depending on running conditions.

Between manifold M and the diaphragm casing 14 is interposed a valve casing 18 having a valve seated port 19 leading by 40 conduit 20 to the manifold, a similar port 21 opening to the atmosphere, and a conduit 22 leading to diaphragm chamber 13.

A double-acting valve 23 within casing 18 is adapted to open and close to control the 45 suction through conduit 22, primarily through lever mechanism L and vacuum operated mechanism connected therewith, and secondarily through lever mechanism l subject to manual operation.

50 Lever mechanism L consists of two toggle jointed levers 24 and 25 fixedly pivoted at 26 on a suitable support and provided at their outer ends with spring arms 27 and 28 connected by tension springs 29.

55 Lever 24 engages the neck 30 of valve 23 between spaced abutment shoulders 31, 32, thereof so that as the lever is suddenly thrust upwardly or downwardly by action of springs 29, one shoulder or the other will receive a thrusting blow, tending to quickly and positively actuate the valve in one direction or the other. A link or rod 33 connects lever 25 with diaphragm 34 of chamber 35 and casing 36—37 which is in suction communication with manifold M by

conduit 38, and is suitably located and held by a support 39.

I have found by experiment that there is a definite point above which the amount of vacuum in the intake manifold will not go 70 as long as the power of the explosions in the engine are turning the engine over, but that as soon as some other power turns the engine over at a speed greater than that at which the engine would idle under the power of its explosions, the vacuum in the intake manifold will increase. This is the case when the machine is coasting and with a retarded or throttled fuel supply. Under such conditions, if the suction on diaphragm 34 is just sufficient to lift lever 25 to about its middle position, any further increase in the vacuum will increase the pull, throwing lever 25 past the dead center, whereupon, springs 29 will lift valve 23. This puts 85 chamber 13 in direct communication with the manifold, shifting valve 9 to close the fuel supply and open the manifold to the air, as in Fig. 3. This position will be maintained as long as the speed of the engine is sufficient to maintain sufficient vacuum in the manifold to hold diaphragm 34 and levers 25, 24 up, subject to the regulated counter pull of springs 40, 41.

These springs are so connected with a resisting support, as bracket 16, as to operate together when the lever 25 is clear up, and by one spring only, as when at the middle position. Thus, spring 40 is always under tension at all positions of the lever, while spring 41 has a loose receding connection, as shown, allowing it to collapse or become inoperative after the lever has dropped sufficiently low. This effect is secured by the fixed and loose nut connections 42, 43, respectively.

By this construction, as soon as the vacuum in the manifold is reduced by admission of air through port 8, springs 40—41 will pull lever 25 down, and if the vacuum is 110 sufficiently reduced, spring 40 will continue to act, throwing the lever down below its dead center position. Springs 29 will then complete the action, thereby thrusting valve 23 downwardly, opening air port 21, and closing vacuum port 19. This destroys the vacuum in chamber 13 so that spring 17 will reverse valve 9 to again open the fuel supply, as in Fig. 1.

The object of using the double springs 120 40—41 is to make adjustment easy. As lever 25 should both rise and fall to a definite extent under certain vacuum conditions dependent on the vacuum in the manifold, it will be seen that one spring cannot easily be adjusted to effect the proper operation at the right time. By supplementing the action of constant spring 40 by action of intermittent spring 41, which is not too strong to entirely counteract the upward movement 125 130

of lever 25, then spring 41 can be easily adjusted so that it will not act against the lever until it has moved upwardly to the desired degree above its dead center with 5 relation to lever 24.

Likewise, spring 41 will become inoperative at positions below the dead center, spring 40 being sufficient to effect continued downward movement of the levers.

10 It is sometimes desirable to close valve 9 to the atmosphere and supply fuel before the speed of the engine decreases sufficiently to effect closing automatically by the mechanism above described. Lever *l* is therefore 15 provided, pivoted at 42^a on a supporting standard 43^a and adapted to be depressed upon the top of stem 30 of valve 23 by action of pivoted link 44 and bell crank lever 45. Said lever is pivoted at 46 and has a 20 pin or stud 47 engaging slot 48 of an operating thrust rod 49, connected with the usual fuel control. Slot 48 allows for the play of the lever *l* under automatic operation, while providing for positive actuation by rod 49, 25 so that opening of the gas throttle throwing rod 49 backwardly with the end of slot 48 against pin 47 will cause lever *l* to shift valve 23, closing port 19 to the manifold, and opening port 21 to the atmosphere, 30 whereupon spring 17 will act.

Under certain conditions, as of momentary high vacuum in the manifold, it is not desirable to open port 8 to the atmosphere. To prevent this, I provide a check valve 50 35 in line 38, of any suitable construction, having a closing valve wing 51 provided with a restricted flow by-pass port 52 (Fig. 2). By this means, any normal drop in the vacuum of the manifold will at once release suction, 40 on diaphragm 34, by opening tendency of the check valve, while any sudden increase in the vacuum will not be transmitted. If necessary, a light spring 53 may be used to ensure closing of the gate, and the port 52 45 may be made sufficiently small to provide for a delay of several seconds before an increased vacuum in the manifold will affect diaphragm 34. If desired, check valve 50 may be omitted.

50 Air inlet valve V is constructed to admit air in an amount varying with the suction of the manifold under the restraining effect of a retracting spring. To this end, it is provided with a controlling gate member 54 within a casing 55 in open communication with the interior of casing 2 through port 8, secured thereto as shown, and having the air inlet ports 7 above referred to. Gate 54 has a stem 56 extending outwardly 55 through a bearing 57 in the end of the casing and a retracting spring 58 is interposed between the casing and a washer 59 held upon the outer end of the stem. The action 60 of the spring is to normally tend to close the gate 54 to reduce the air supply to a

minimum. To this end, a variable leakage space is provided between the gate 54 and casing 55 by one or more set screws 60 which may be adjusted as desired to admit a minimum amount of air when the valve is 70 retracted.

The construction and operation will be readily understood from the foregoing description. It effects a very material economy in fuel, and at the same time effectually 75 prevents the formation of carbon in the cylinders.

Various changes or modifications may be made by the skilled mechanic in design, proportions, or other details, or application 80 to any particular type or form of carburetor, manifold, or other conditions of installation, and I therefore do not desire to be limited to the exact construction shown.

What I claim is:

1. In an internal combustion engine, the combination with the intake conduit, of a casing communicating therewith and with the fuel supply and atmosphere respectively, a rotatably mounted valve therein between the intake conduit and the fuel supply, means subject to suction of the engine for actuating said valve, and means also subject to the suction of the engine controlling 90 the operation of the valve actuating means.

2. In an internal combustion engine, the combination with the intake conduit, of a casing communicating therewith and with the fuel supply and atmosphere respectively, a rotatably mounted valve therein between the intake conduit and the fuel supply, means subject to suction of the engine for actuating said valve, means also subject to the suction of the engine controlling 100 the operation of the valve actuating means, and means also subject to engine suction for opening communication to the atmosphere.

3. In an internal combustion engine, the combination with the intake conduit, of a 110 casing communicating therewith and with the fuel supply and atmosphere respectively, a rotatably mounted valve therein, means subject to suction of the engine for actuating said valve, and a separate air inlet valve 115 subject to engine suction adapted to supply air to the intake conduit when the rotatably mounted valve is in a position to open communication therewith.

4. In an internal combustion engine, the 120 combination with the intake conduit, of a casing communicating therewith and with the fuel supply and atmosphere respectively, a rotatably mounted valve therein, means subject to suction of the engine for 125 actuating said valve, and a separate air inlet valve casing communicating with the rotatable valve casing and with the atmosphere and having a spring-retracted valve and adjustable abutment bearings therefor. 130

5. In an internal combustion engine, the combination with the intake conduit, of a casing communicating therewith and with the fuel supply at opposite sides and laterally with the atmosphere, a valve member therein having a circulation passage for putting the intake conduit into communication with the fuel supply and a wall for closing the atmosphere supply in such position, and when reversed to put the intake conduit into communication with the atmosphere and to close the fuel supply by said wall, and means subject to suction of the engine for actuating said valve.
- 15 6. In an internal combustion engine, the combination with the intake conduit, of a casing communicating therewith and with the fuel supply at opposite sides and laterally with the atmosphere, a valve member therein having a circulation passage for putting the intake conduit into communication with the fuel supply and a wall for closing the atmosphere supply in such position, and when reversed to put the intake conduit into communication with the atmosphere and to close the fuel supply by said wall, means subject to suction of the engine for actuating said valve, and a reversing spring for said valve.
- 30 7. In an internal combustion engine, means for cutting off the fuel supply and for opening the combustion chamber to the atmosphere consisting of a valve casing communicating with the intake conduit, the fuel supply, and the atmosphere respectively, a valve therein provided with an actuating lever, a movable head subject to engine suction connected to said lever, a casing for said head, a controlling valve adapted to connect the casing with the intake conduit and with the atmosphere respectively, a diaphragm and chamber having a suction conduit connected with the intake conduit, means connected with the diaphragm and with the controlling valve, and means independent of said means for actuating the controlling valve.
- 45 8. In an internal combustion engine, means for cutting off the fuel supply and for opening the combustion chamber to the atmosphere consisting of a valve casing communicating with the intake conduit, the fuel supply and the atmosphere respectively, a valve therein provided with an actuating lever, a movable head subject to engine suction connected to said lever, a casing for said head, a controlling valve adapted to connect the casing with the intake conduit and with the atmosphere respectively, a dia-
- phragm and chamber having a suction conduit connected with the intake conduit, means connected with the diaphragm and with the controlling valve, and independent lever mechanism for actuating the controlling valve.
- 60 9. The combination with the intake conduit and fuel supply valve of an internal combustion engine and a suction-actuated operating element for said valve communicating with the intake conduit, of a valve interposed between said element and the conduit operable to open the said element to the conduit or to atmosphere respectively, co-acting spring controlled lever mechanism for actuating said valve, operating means therefor also subject to engine suction, and independent lever mechanism for actuating the controlling valve.
- 65 10. Controlling valve mechanism consisting of a valve casing having circulating portions adapted to communicate with an engine intake conduit, with a suction chamber, and with the atmosphere respectively, a valve alternately controlling the circulation to the intake conduit and atmosphere, a pivoted lever engaging said valve, a pivoted oppositely extending suction actuated lever, and a spring connecting said levers beyond their pivoted bearings.
- 70 11. Controlling valve mechanism consisting of a valve casing having circulating portions adapted to communicate with an engine intake conduit, with a suction chamber, and with the atmosphere respectively, a valve alternately controlling the circulation to the intake conduit and atmosphere, a pivoted lever engaging said valve, a pivoted oppositely extending lever, a spring connecting said levers beyond their pivotal bearings, and a suction actuated element communicating with the intake conduit.
- 75 12. Controlling valve mechanism consisting of a valve casing having circulating portions adapted to communicate with an engine intake conduit, with a suction chamber, and with the atmosphere respectively, a valve alternately controlling the circulation to the intake conduit and atmosphere, a pivoted lever engaging said valve, a pivoted oppositely extending lever, a spring connecting said levers beyond their pivotal bearings, a suction actuated element communicating with the intake conduit, and a retracting spring for the suction actuated lever.
- 80 13. In testimony whereof I hereunto affix my signature.
